UNITED STATES PATENT OFFICE

DONALD B. BRADNER, OF HAMILTON, OHIO

COMPOSITION FOR PRODUCING IRRITATING SMOKE CLOUDS

No Drawing. Application filed January 24, 1928. Serial No. 249,215.

(GRANTED UNDER THE ACT OF MARCH 3, 1883, AS AMENDED APRIL 30, 1928; 370 O. G. 757)

This invention described herein may be manufactured and used by or for the Government for Government purposes without the payment to me of any royalty thereon.

5 This invention relates to smoke clouds which, in addition to their power of obscurrence, produce an irritating or lachrymating effect upon persons.

These irritating smoke clouds are designed 10 to fulfill a much desired need in military operations, for in addition to the screening effect produced by the cloud, the irritating effect operates to impede the progress of opposing troops. By forming irritating smoke clouds, 15 the opposing troops are forced to wear protecting devices, such as gas masks, and this additional burden upon the troops tends to impede their progress.

I have found that chloracetophone and 20 other similar irritants, for example the other halogen derivatives of acetophenone, can be employed with certain smoke-producing materials, for example, white phosphorus, which burns spontaneously in the air, and the combustion of the white phosphorus will take at a sufficient temperature to volatilize the chloracetophone or similar irritant, but at a temperature below that at which the lachrymator will substantially decompose within the time 25 required for the volatilization. This is a very important feature of my invention, because a combination of irritant and smoke-producing agent, wherein the smoke-producing agent will burn at a temperature to cause high decomposition of the irritant in order to produce the desired volatilization, would be 30 satisfactory, because it is desired to maintain the irritant or lachrymator undecomposed when volatilized in the air in order that the benefit of the irritating and lachrymating properties thereof be preserved. In my mixture the white phosphorus will consume substantially all of the oxygen in the air immediately around the particles of burning phosphorus, so that no oxidation of the chloracetophone, or other similar irritant, takes place. The low temperature of combustion of the phosphorus favors a low thermal decomposition of the chloracetophone.

50 Specific examples of preparing my irritat-

ing smoke-producing composition are as follows:

Example I.—Equal weights of white phosphorus and chloracetophenone are placed in a container which is heated so as to melt both components of the mixture, and the mass is then agitated by shaking or otherwise until the mixture has cooled below its freezing point. This results in an intimate mixture of the two constituents. Although the above 55 proportions of phosphorus and chloracetophenone are preferable, good results are also obtained with 25 to 75 percent of each of these ingredients.

Example II.—Molten chloracetophenone is added to molten phosphorus with stirring, and the charge then introduced while in a partially solid state into a suitable container.

Example III.—The white phosphorus and chloracetophenone are separately melted and grained and the container is then charged with a mixture of these two grained substances. In order to facilitate the handling of the phosphorus pellets these operations are preferably carried out in an inert atmosphere, or under water, etc.

The apparatus holding the mixture of chloracetophenone and white phosphorus produced by either of the methods shown above, is preferably equipped with a suitable explosive charge and a firing mechanism therefor. Upon firing this charge, the container is ruptured and the mixture is scattered in fine particles into the air. The phosphorus ignites and in burning volatilizes the chloracetophenone. The effect produced is a cloud of good obscuring power which also possesses a powerful lachrymating action.

An alternative apparatus consists in using a container for the chloracetophenone and white phosphorus which does not rupture but merely melts away at a given rate and allows the mixture to flow out onto the ground where the phosphorus burns and volatilizes the chloracetophenone.

Another method of using my irritating smoke-producing mixture is to place the mixture in the form of lumps or aggregates into shallow pans, or even directly upon the ground and allow the phosphorus to ignite

spontaneously, or if desired by some mechanical or chemical means.

The present invention is not limited to the specific details set forth in the foregoing examples which should be construed as illustrative and not by way of limitation and in view of the numerous modifications which may be effected therein without departing from the spirit and scope of this invention, it is desired that only such limitations be imposed as are indicated in the appended claims.

I claim:

- 15 1. In a composition for producing irritating smoke cloud, a mixture of white phosphorus and a halogen derivative of acetophenone.
- 20 2. In a composition for producing irritating smoke clouds, an intimate mixture of grains of white phosphorus and a halogen derivative of acetophenone.
- 25 3. In a composition for producing irritating smoke clouds, a mixture of white phosphorus and chloracetophenone.
4. In a composition for producing irritating smoke clouds, an intimate mixture of grains of white phosphorus and grains of chloracetophenone.

In testimony whereof I affix my signature.

30 DONALD B. BRADNER.
